United States Patent Office

Des. 208,950
Patented Oct. 17, 1967

208,950

JUG

Raymon E. Hobbs and James A. Shepler, Toledo, Ohio, assignors to Owens-Illinois, Inc., Toledo, Ohio, a corporation of Ohio

Filed June 6, 1966, Ser. No. 2,581

Term of patent 14 years

(Cl. D58—5)

FIG. 1

FIG. 2

The back is a mirror image of the front.

The characteristic features of this design reside in the configuration shown in full lines on the drawing.

We claim:

The ornamental design for a jug, substantially as shown and described.
